US00D938203S

(12) **United States Design Patent** (10) Patent No.: **US D938,203 S**
 Cichuta et al. (45) Date of Patent: **** Dec. 14, 2021**

(54) **DISPLAY RACK FRONT**(71) Applicant: **Lidl Stiftung & Co. KG**, Neckarsulm (DE)(72) Inventors: **Denis Cichuta**, Neckarsulm (DE); **Oliver Menke**, Neckarsulm (DE); **Philipp Bange**, Neckarsulm (DE); **Hernan De La Vega**, Neckarsulm (DE)(73) Assignee: **Lidl Stiftung & Co. KG**, Neckarsulm (DE)(**) Term: **15 Years**(21) Appl. No.: **29/717,466**(22) Filed: **Dec. 17, 2019**
